UNITED STATES PATENT OFFICE.

HENRY B. RICHARDSON, OF ATTLEBORO, MASSACHUSETTS, ASSIGNOR TO SMITH & RICHARDSON, OF ATTLEBORO, MASSACHUSETTS.

BRACELET.

SPECIFICATION forming part of Letters Patent No. 788,221, dated April 25, 1905.

Application filed July 15, 1904. Serial No. 216,680.

To all whom it may concern:

Be it known that I, HENRY B. RICHARDSON, a citizen of the United States, residing at Attleboro, in the county of Bristol and State of Massachusetts, have invented a new and useful Improvement in Bracelets, of which the following is a specification.

This invention has reference to an improvement in bracelets, and more particularly to an improvement in spring-bracelets.

The object of my invention is to improve the construction of bracelets, whereby a new and novel effect in bracelets is produced.

A further object of my invention is to construct bracelets having an artistic and expensive appearance at a low cost of manufacture.

My invention consists in the peculiar and novel construction of a bracelet having a spring-band core in the form of a hoop with overlapping ends, a flexible woven-wire tubular casing covering the core, and ornamental ends secured to the overlapping ends of the bracelet by solder or other means, as will be more fully set forth hereinafter.

Figure 1 is a perspective view of my improved bracelet. Fig. 2 is a perspective view of the spring-band forming the core of the bracelet. Fig. 3 is an enlarged face view of the flat woven-wire stock from which the tubular casing of the bracelet is constructed. Fig. 4 is an enlarged end view of the woven-wire stock. Fig. 5 is an enlarged end view of the woven-wire stock, showing the first step in forming the flat stock into a tubular casing. Fig. 6 is an enlarged end view of the completed tubular casing formed from the flat woven-wire stock, and Fig. 7 is an enlarged transverse sectional view through the tubular woven-wire casing and the spring-band forming the core of the bracelet.

In the drawings, *a* indicates the spring-band

forming the core of the bracelet; *b*, the flat woven-wire stock; *b'*, the locking-coil; *b²*, the completed woven-wire tubular casing formed from the stock *b*, and *c c* the ornamental ends of the bracelet. The spring-band *a* is in the form of a hoop, having the overlapping ends *a' a'*, as shown in Fig. 2. The flat woven-wire stock *b* is constructed by forming a wire into a screw-coil and screwing a series of the wire coils together, as shown in Fig. 3, forming a flat woven-wire stock of any width or length desired. The flat woven-wire stock is doubled lengthwise, as shown in Fig. 5, and formed into a tubular casing by screwing the locking-coil *b'* into the coils forming the edge of the stock, as shown in Fig. 6. The spring-band *a* forming the core is now pushed into the woven-wire tubular casing (shown in Fig. 7) and the ornamental ends *c c* secured to the overlapping ends *a' a'* by solder or other means.

Having thus described my invention, I claim as new and desire to secure by Letters Patent—

1. In a bracelet, the combination of the spring-metal band *a* and the flexible woven-wire tubular casing *b²* constructed from the flat woven-wire stock *b*, and the locking-coil *b'*, as described.

2. In a bracelet, the combination of the spring-metal band *a*, the flexible seamless woven-wire tubular casing *b²* formed by interwoven coils of wire, and the ornamental ends *c c*, as described.

In testimony whereof I have signed my name to this specification in the presence of two subscribing witnesses.

HENRY B. RICHARDSON.
